Attorney

UNITED STATES PATENT OFFICE.

LOUIS H. OLDENBURG, OF OSHKOSH, WISCONSIN.

BARBER'S-APPLIANCE TROLLEY.

1,362,580.

Specification of Letters Patent. Patented Dec. 14, 1920.

Application filed November 21, 1919. Serial No. 339,671.

To all whom it may concern:

Be it known that I, LOUIS H. OLDENBURG, a citizen of the United States, residing at Oshkosh, Wisconsin, have invented certain new and useful Improvements in Barbers' Appliance Trolleys, and I do hereby declare the following to be a full, clear, and exact description of the invention, such as will enable others skilled in the art to which it appertains to make and use the same.

My invention relates to barber shop equipment, one of its general objects being that of providing safe, convenient and easily manipulated means whereby one or more electrically operated appliances can readily be used at a number of different chairs in the barber shop, and to provide this arrangement in such a manner that all parts of the same will normally be entirely out of the way of both the barbers and their patrons. Another object is that of providing a portable mounting for electrically operated barber shop appliances which will not involve any floor stand, and which can readily be installed in direct connection with the needed electric light fixtures, so as not to require separate wall brackets or ceiling pendants. Still another object is that of providing a portable and adjustable mounting for electrically operated barber shop appliances which will display advertising when the appliances are in position for use, and desirably to provide this in such a manner that advertising may partly be displayed directly and partly by reflection from the wall mirrors. A further object of my invention is that of providing a simple and automatically acting spring-retracted support for the appliances, whereby this can be raised or lowered as desired while maintaining the operative connection to the supply of current.

In modern barber shops, it has become more and more customary to use electrically driven clippers and massaging vibrators, for which purpose it has been customary to provide a pair of such electrical appliances adapted to be connected interchangeably to a single electric motor. To support these, it has been customary to mount the motor on a floor stand, and in order to have this stand readily portable it has commonly been built of light weight. Consequently, such stands are often upset by men getting into or out of the barber chairs, particularly as

the height at which the motor is desirably mounted for permitting the employment of a relatively short flexible shaft makes the stand somewhat top-heavy. Furthermore, the electrical connection from the motor to the supply of current requires a flexible cord over which men are apt to trip and which either drags along the floor for a considerable length to permit the desired varying in position of the stand, or else has to be disconnected from one socket and connected to another whenever the stand has to be changed in position. Owing to the presence of both the stand and the cord on the floor, accidents have been frequent and often expensive in the resulting repairs.

To overcome these and other objections to the arrangement heretofore in use, my invention aims to provide supports and connections for the electric motor and the appliances driven by the same, with the supporting means so arranged that the entire equipment will normally be above the heads of both the barbers and their patrons, so that the floor will still be left clear even when the motor and the appliances are in operative position. Furthermore, my invention aims to arrange the supporting means so that the motor and the appliances associated therewith can instantly be shifted from one to another of the various positions in which they can be conveniently employed at the different chairs, and to provide automatic means for sustaining the motor and the appliances at various heights. Still further and also more detailed objects will appear from the following specification and from the accompanying drawings, in which—

Figure 1 is a transverse vertical section through one side of the barber shop equipped with my invention.

Fig. 2 is an enlarged and fragmentary elevation taken at right angles to Fig. 1 from the right hand side of Fig. 1.

Fig. 3 is an enlarged central and longitudinal section through a portion of the trolley tube and parts associated therewith.

Fig. 4 is an enlarged transverse vertical section taken along the line 4—4 of Fig. 2.

In the drawings, which show a desirable embodiment of my invention, though by no means the only advisable one, the lighting equipment of the shop includes a series of lamps 1 desirably located directly above the several barber chairs, each of which

lamps is supported by a bracket fixture from the adjacent wall of the shop. Each bracket fixture in the illustrations includes a horizontal arm 2 connected to a diagonal support 3 by a coupling member 4. The lamp socket supported by each bracket is connected to the supply of current through wires concealed in one of the hollow bracket portions 2 or 3 after the usual manner, and the brackets are desirably equal in size and aligned with each other parallel to the adjacent wall, so that the coupling members 4 are all in alinement.

Jointly supported by these coupling members, as by hanger brackets 5, is a tube 6 which is slotted at its bottom as shown in Fig. 4. This tube affords a runway or track for the wheels 7 of a trolley which is here shown as including a web 8 extending vertically through the slot in the tube. Secured to a curved flange 9 on the lower end of this web 8 is the casing 10 of a roller shade constructed after the usual manner of spring shade rollers, but with a spring of unusual strength and tension for the purpose hereafter described. The curtain 11 associated with the spring roller is of strong curtain material which carries at its lower end a carrier member, such as a hook plate 12 equipped with suitable formations for supporting both the electric motor and the appliances which are to be used in connection with the latter. For example, this carrier member may include a fork 13 to which the motor 14 is swiveled, and a pair of hooks 15 one of which normally supports the clipper while the other normally supports the vibrator. Connection is made to the motor through a flexible cord 16 which desirably extends to a spring take-up reel 17 disposed at some convenient point substantially intermediate of the range through which the support is to be moved along the shop. For example, where the tube 6 is supported by a series of brackets as in Fig. 1, the reel 17 may be placed near and below the center bracket. The spring reel used for winding up the cord has a spring of such strength as automatically to keep the cord approximately taut, while the spring used in connection with the roller is of such strength as to wind the curtain 11 up readily when the hook plate 12 is lifted, and this roller also has associated with it a suitable friction arrangement for holding the curtain in its raised position against the weight of the parts supported by it, so as to prevent the curtain and the appliances from gradually creeping downwardly when not wanted.

With the parts arranged as above described, it will be obvious from the drawings that with the curtain raised, the motor 18 and the appliances associated therewith will normally be supported entirely out of the range of persons in the shop, thereby

leaving the floor clear. When either of the appliances is to be used, the entire shade roller mechanism is moved along its wheeled track longitudinally of the shop to a convenient position near the chair at which the appliance is to be employed, and the curtain is then lowered so as to bring the motor to a suitable height for enabling the flexible cord to bring the appliance into convenient position for use. In doing this, the current supplying cord 16 follows the motor, this cord being automatically fed off the reel 17, but correspondingly retracted when the appliance is hooked back on the plate 12 and the curtain is raised. Then the appliances are again out of the way, ready to be moved whenever desired to some other chair in the shop.

As a further feature of my invention, I desirably equip either one or both faces of the curtain 11 with advertising matter, thereby enabling the owner of the shop to add to his earnings. Such advertising when placed on the outer face of the curtain, or the right hand face in Fig. 1, is displayed after the usual manner, while that on the opposite face is reversed side for side, so that it will be readable when reflected from the wall mirror 19. However, while I have heretofore described my invention in an embodiment in which the trolley tube or track is supported by the brackets of electric light fixtures, and in which I display advertising on both faces of the curtain, I do not wish to be limited to these or other details of the construction and arrangement above disclosed, it being obvious that the same might be varied in many ways without departing from the spirit of the appended claims.

I claim as my invention:

1. In a barber shop appliance, in combination with an overhead support and a mirror disposed rearwardly of the support, a rolling curtain borne by the support, a barber's implement borne by the curtain, said curtain having a rear exposed surface to receive reversed advertising matter so that same will be readably reflected in the mirror and means to support the curtain under tension.

2. In a barber shop appliance, an overhead track, a spring roller, means to mount the roller from said track so that the roller may be moved lengthwise of the track and with its longitudinal axis parallel to the track, a curtain borne by the roller, and a device carried by the lower end of the curtain for supporting a barber's appliance.

3. Means for adjustably supporting electric appliances, including a holder for the appliances, a flexible curtain carrying the holder, and a spring roller to which the curtain is attached and on which it is adapted to be wound by the tension of the spring, the curtain having advertising legends on both

105

110

115

125

130

faces thereof, and the legend on one face being reversed side for side, for readable reflection in a mirror.

4. Means for adjustably supporting electric appliances, including a holder for the appliances, a flexible curtain carrying the holder, and a spring roller to which the curtain is attached and on which it is adapted to be wound by the tension of the spring, and shiftable mounting for the spring roller, whereby the aforesaid elements may all be freely moved in directions longitudinal of the axis of the roller.

5. Means for adjustably supporting an electric appliance, including a spring roller shade having its lower end equipped for holding the said appliance, a track for the roller shade on which the latter is bodily shiftable longitudinally of its axis and with the latter parallel to the track, a flexible conductor leading to the electric appliance, and means shiftable with the roller shade for guiding the said conductor.

6. In a barber shop appliance, a track, an elongated casing, means to slidably support the casing from the track and with its longitudinal axis parallel to the track, a spring roller in the casing, a curtain borne by the roller, a motor support pivotally borne by

the free end of the curtain, and a barber's 30 appliance flexibly connected to the motor.

7. Means for adjustably supporting a motor-driven appliance in a barber shop, comprising an overhead track, a spring shade roller suspended therefrom and movable lengthwise thereof and with its longitudinal axis parallel thereto, and supporting means carried by the shade of the roller for supporting the motor-driven appliance; the spring of the shade roller being of such 40 strength as to balance the combined weights of the said shade, appliance and supporting means.

8. In a barber shop appliance, a track, an elongated casing, means to slidably support 45 the casing from the track and with its longitudinal axis parallel to the track, a spring roller in the casing, a curtain borne by the roller, an appliance support pivotally borne by the free end of the curtain, means to pivot 50 the appliance in the support, said first means being perforated, and a take-up reel having a cord extending through the perforation of said means and connected to the appliance borne by the appliance support. 55

Signed at Chicago, November 15, 1919.

LOUIS H. OLDENBURG.
